UNITED STATES PATENT OFFICE.

SAMUEL AGUSTUS GILL, OF NEVADA, IOWA.

DESIGN FOR AN ADVERTISING SIGN.

Application filed January 22, 1926. Serial No. 16,215. Term of patent 3½ years.

To all whom it may concern:

Be it known that I, SAMUEL A. GILL, a citizen of the United States of America, and a resident of Nevada, Story County, Iowa, have invented a new, original, and ornamental Design for an Advertising Sign, of which the following is a specification, reference being had to the accompanying drawing, forming part hereof.

I claim:

The ornamental design for an advertising sign, as shown.

SAMUEL AGUSTUS GILL.
